Application December 5, 1932, Serial No. 645,730

36 Claims. (Cl. 51—103)

This invention relates to improvements in machine tools and especially to improvements in lapping machines.

An object of this invention is the provision of a lapping machine particularly adapted for lapping cylindrical or circular work pieces that cannot be axially shifted during the lapping operation.

Another object of the invention is the provision of a lapping machine for rapidly and simultaneously lapping individual portions of a circular or cylindrical work piece.

A further object of the invention is the provision of a lapping machine for lapping the shoulders of cylindrical work pieces, that is, lapping that portion of a cylindrical work piece that lies adjacent an enlarged collar or flange on the work.

A still further object of the invention is the provision of a lapping machine for lapping the flat lateral faces of an enlarged portion of a work piece.

It is also an object of this invention to provide an improved lapping machine for simultaneously lapping cylindrical portions of a work piece which lie adjacent an enlarged flange or collar and for lapping one or both sides of the said flange or collar simultaneously with the lapping of the cylindrical portions of the work.

It is also a further object of this invention to provide an improved lapping machine for accomplishing the above objects in which the work is automatically presented to the lapping wheels or members and automatically ejected therefrom.

The invention also contemplates an improved control mechanism for initiating and controlling the several functions and operations of the machine.

Other objects and advantages of the present invention should be readily apparent by reference to the following specification considered in conjunction with the accompanying drawings, forming a part thereof, and it is to be understood that any modifications may be made in the exact structural details there shown and described, within the scope of the appended claims, without departing from or exceeding the spirit of the invention.

In the drawings:

Figure 1 is a front elevation of the improved lapping machine of this invention.

Figure 2 is a top plan view of the machine as seen in Figure 1, the truing mechanisms being removed and the guard shown in section.

Figure 3 is an end elevational view, as seen from the left hand end of Figures 1 and 2.

Figure 4 is a fragmentary horizontal sectional view, as seen along the line 4—4 on Figure 1.

Figure 5 is a fragmentary sectional view taken on line 5—5 of Figure 1 illustrating particularly the manual control means for varying or adjusting the relative speeds of the wheels.

Figure 6 is a view or elevation taken through the throat of the machine showing the work in position with respect to the lapping members.

Figure 7 is a diagrammatic view illustrating the hydraulic control circuits involved in the invention.

Figure 8 is a vertical sectional view through the throat of the machine, as seen particularly along line 8—8 on Figure 1.

Figure 9 is a vertical sectional view taken at right angles to the plane or section of Figure 8, as seen along line 9—9 on said Figure 8.

Figure 10 is a fragmentary sectional view taken on line 10—10 on Figure 8.

Figure 11 is a sectional view through the control valve for the hydraulic circuit and is taken on line 11—11 on Figure 1.

Figure 12 is a horizontal sectional view showing the speed variation mechanism and is a view taken substantially on line 12—12 on Figure 3.

Figure 13 is a sectional view taken on line 13—13 on Figure 2.

Figure 14 is a sectional view taken on line 14—14 on Figure 4.

Figure 15 is a sectional view taken on line 15—15 on Figure 11.

Throughout the several views of the drawings, similar reference characters have been employed to denote the same or similar parts.

Since this application and our co-pending application Serial No. 622,662, filed July 15, 1932, have certain subject-matter in common, we have made claims to such common subject-matter in the said copending application.

As was suggested above, the machine of this invention is particularly adapted for providing a flat lapped finish on work pieces. By this is meant that the work is provided with a surface that is substantially devoid of alternate grooves and ridges, which are produced by a grinding machine during the final grinding operation. These grooves and ridges are generally circumferential of the work pieces and are formed by the abrasive grains of which the grinding wheel is composed. It is to be understood that the grinding wheel, in usual grinding practice, is rotated at its efficient grinding rate of speed, namely about 6000 peripheral feet or more a minute. It is also appreciated that the depth of the groove and the regularity of

the ridges depend to a large extent on the grade or fineness of the said grains of which the wheel is composed. When the work piece resulting from such a grinding operation is placed in operation 5 in the mechanism or apparatus of which it forms a part the ridges are soon worn away so that while the work piece probably fitted its bearing when inserted therein, it will, shortly after being placed in use, be loose therein due to the wearing 10 away and resultant flattening out of the said ridges.

The machine of this invention removes these ridges left by the grinding operation and does so 15 without forming any of its own and thereby our invention insures that the work piece fits its bearing, if, as is usually the case, it is intended for reception in or by a bearing, for a considerably longer period of time after being placed in use. The surface, therefore, produced by the lapping 20 machine is flat or plane (though it may be curved) as compared to the ridged surface of the piece after it leaves the grinding machine. This lapped surface is produced on the present machine by wheels composed of abrasive grains, but due to 25 such factors as the fact that the differential in speed between the wheel and work is much lower than that between the grinding machine wheel and work, the results are entirely different.

Specifically the machine comprises a bed 15 (Figure 1) having formed on its upper surface opposed raised pads 16 and 17 (Figure 2) on the upper surface of which are respectively disposed the lapping head 18 and control head 19. Each of the heads has its base plate extending beyond 30 the longitudinal edges of its supporting pad, which resulting extending portions are formed into down-turned flanges 20 and 21, see Figure 3. Each of the heads is in turn provided on the under surface of its base plate with a groove 22 respectively receiving therein guide members 23 and 24 (Figures 2 and 3). These guides 23 and 24 are pivoted to be adjustable about vertical axes at their inner adjacent ends by pivots 25 and 26 (Figure 2) to their respective pads and are hence 35 adjustable for correspondingly shifting their heads. From this it will be seen that the angle between the said guides may be changed, thus to dispose said heads at an angle to one another.

Since the means for angling the guides is the 40 same for each, it is deemed sufficient if but one of them be described in detail; accordingly the guide 23 is provided at its outer end with a depending lug 27 (Figure 13) received in a passage or slot 28 formed laterally of a lug or bracket 29 (Figures 2 and 3) projecting from the outer end of the pad 16. The bracket 29 has extending through 45 opposite sides thereof adjusting screws 30 and 31 (Figures 2, 3 and 13) engaging opposite faces of the lug 27 and co-operating with one another to position the said guide 23 relative to the bed. The adjusting screws 30 and 31 are provided with lock nuts 32 for securing same and consequently 50 the guide in adjusted positions. A similar arrangement, as above-mentioned, is provided for adjusting the guide 24; both adjusting arrangements are clearly indicated and shown in Figure 2.

The heads 18 and 19 are adapted to be actuated 55 relative to their supporting pads toward and from each other along paths determined by the adjustment of the guides 23 and 24 by similar means only one of which will be described in detail. The lapping head 18 has mounted in its outer end face a nut 33 (Figures 1 and 2) in threaded engagement with an adjusting screw 34 which is in turn

5 rotatably journaled in a bracket 35 extending upwardly from the outer end of the guide 23. The adjusting screw 34 extends beyond the bearing bracket 35 and has secured to its projecting portion a hand or pilot wheel 36 whereby the said screw is rotated.

In order to secure the heads in adjusted positions, the down-turned flanges 20 and 21 thereof each has underlying it a clamp plate 37 (Figure 3) co-operating with manually actuated clamp 10 screws 38 operable by the handles 39 for securely engaging underneath laterally extending flanges of the raised pads and clamping them between the base plates of the heads and the clamp plates 37.

The head 18 is the operating or lapping head 15 and comprises a housing member 40 (Figures 1 and 2 and 3) including a base plate 40a (Figure 4) and an upstanding face plate 41 against which is butted the wheel carriage 42. The plate 41 is provided substantially centrally of its width with 20 an aperture 43 (Figure 4) the axis of which is in a horizontal plane containing the axis of the shaft or spindle 44 carried by the carriage 42 when the said shaft or spindle is horizontally disposed. Received in the aperture 43 is a pivot pin 66 connecting the head 18 and carriage 42 and about which the carriage may be oscillated or swung to dispose the axis of the shaft or spindle 44 at an angle to the horizontal. The carriage 42 is provided with arms 45 and 46 (Figure 4) in which are 25 mounted anti-friction bearings 47 and 48 forming journals for the spindle 44. The spindle 44 has mounted thereon a sleeve or collet 49 for receiving thereon a plurality of lapping members or 30 wheels 50, 51 and 52. The wheels 50 and 51 are 35 spaced from one another by a sleeve 53, while the wheels 51 and 52 are in turn spaced from one another by a sleeve 54. The wheels and spacing sleeves are clamped between an upstanding flange 55 formed integral with or secured to one end of 40 the collet 49, and a nut 56 threaded on the opposite end of the collet 49. The particular spacing thus provided by way of illustration, as shown in the drawings (see Figure 4) is to take care of the spaced bearings 57, 58 and 59 of a cam shaft 45 such as is used on internal combustion engines. It is to be understood, however, that the machine is not limited to the production of the particular work piece illustrated in the drawings.

In order to clamp the carriage 42 in its selected 50 position of adjustment about the pivot 66, the carriage has projecting from it a pair of clamp screws 60 and 61 (see Figure 3) which extend through arcuate slots 62 and 63 formed in the plate 41. The carriage 42 has further extending 55 from it a clamp bolt 64 (Figure 3) passing through an elongated slot 65 likewise formed in the plate 41. In order to effect the adjustment or oscillation of the carriage 42 about the axis of the pivot 66, the plate 41 has an outwardly extending boss 60 67 (Figures 1 and 3) through which is threaded an adjusting screw 68 that contacts with a roller or the like 69 carried by the clamping screw 60.

From the foregoing it will be noted that the carriage 42 may be oscillated or swung about the 65 axis of the pivot or trunnion 66 (Figure 4) for disposing the axis of the spindle 44 and parts carried thereby at an angle to the horizontal. It will further be noted that through the adjusting screws 30 and 31 the guide 23 may be adjusted 70 about the axis of its pivot 25 for thereby disposing the axis of the spindle 44 at an angle within the plane which is parallel to the horizontal plane through the machine. In other words, the axis of the spindle 44 and parts carried thereby is ad- 75

justable in planes at right angles to one another for thereby skewing the axis of the lapping wheels with respect to the axis of the work piece.

By reference particularly to Figure 6 it will be noted that the wheels 50, 51 and 52 are of increasing diameter so that they are in effect sections of a conoidal member. The term "conoidal" is employed in designating same for the reason that due to the horizontal angular relationship between the axis on which these wheels rotate and the axis of the work, it is necessary that the surfaces be slightly concaved in order to provide proper contact between the wheels and the work, the lapping members therefore tending to fit or lap around the work piece. It is of course to be understood that the amount of concaving applied to what may be considered a frustro-conical wheel member, of which only sections 50, 51 and 52 are employed, is as an entirety quite slight, and the concavity is therefore illustrated in greatly exaggerated form to be visually perceptible in the reduced scale of the drawings.

The head 19 is the work controlling head and, similar to the head 18, includes a bracket or housing member 70 (Figures 1, 2 and 4) having a base plate 70a (Figure 4) and an upstanding face plate 71 against which is butted a carriage 72. The plate 71 is provided with an aperture 73 substantially centrally of the width of the plate 71 lying in the plane containing the axis of the spindle or shaft 74 carried by the carriage 72. Journaled in the aperture 73 is a trunnion or pin 75 having integral therewith or secured thereto a key 76 received in a groove or keyway 77 formed in the carriage 72. The carriage 72 also has extending from it a pair of arms 78 and 79 respectively containing anti-friction bearings 80 and 81 forming journals for the spindle 74. The spindle 74 has mounted thereon a sleeve or collet 82 axially spaced of which are the friction control or regulating wheels 83, 84 and 85, illustratively three, to match the lapping wheels. The wheels 83 and 84 are spaced from one another by the sleeve spacing member 86, while the wheels 84 and 85 are likewise spaced from one another by a sleeve or spacer 87. The wheels and spacers are clamped to the collet 82 by means of flange 88 integral with or secured to the collet 82 and a nut 89 threaded on said collet. The wheels 83, 84 and 85 are juxtaposed to wheels 50, 51, 52 (Figure 4) and are positioned to engage with the bearing portions 57, 58 and 59 of the work piece at points disposed on the other side of its axis from the points thereof engaged by the lapping wheels 50, 51 and 52.

The carriage 72 is adapted to be oscillated or adjusted about the axis of the trunnion or pivot 75 by a screw 90 (Figure 1) threaded into a boss 91 projecting from the rear surface of the plate 71. This adjusting screw 90 engages with a roller or the like 92 carried by a clamping bolt 93, this construction being similar to the already described adjusting means carried by the lapping or operating head. A further clamping screw 94 projects from the carriage 72 (see Figure 4) and this clamping screw 94 and the clamping screw or bolt 93, extend through arcuate slots 96 and 95, respectively. The heads 97 and 98 respectively of clamp screws 93 and 94 are received in T-shaped slots 99 and 100 (Figure 4) formed in the carriage 72. These T-shaped slots prevent rotation of the clamping screws when the clamping nuts thereof are actuated in either a clamping or releasing direction and at the same time permit a lateral ad-

justment of the carriage 72 relative to the housing member 70.

The carriage 72, as is already intimated above, is mounted so as to be adjusted axially of the spindle 74 or laterally of the bed 15 for thereby accurately aligning the opposed lapping and control wheels and also to take up for wheel wear, as will later appear. To effect this adjustment, the carriage 72 has projecting from opposite sides thereof studs 101 and 102 (Figure 4) in each of which is formed a threaded hole for the adjusting screws 103 and 104. The said adjusting screws engage on their inner ends with the vertical faces of the plate 71, as is better shown in Figure 4. The adjustment of the carriage 72 is limited to take place in a direction axially of the spindle 74 through the interengagement of the above described key 76 and keyway 77. By this construction, no interference is offered to the oscillation or tilting adjustment of the carriage about the axis of the stud 75 since the key 76 is in the same plane as the stud 75 and is oscillatable with the stud about its axis.

The work piece has formed thereon, adjacent the bearing portion 59, an enlarged flange or collar 105 (Figure 4) which is to have its opposite surfaces lapped. This lapping is effected on the side adjacent the bearing 59 by the lateral or side face 106 of the control wheel 85, and on the opposite side by the lateral face (or edge) 107 of the wheel 108. The wheel 108 is mounted on a sleeve or collet 109 between a flange 110 thereon and a clamping nut 111. The collet 109 is keyed on one portion of the spindle 74 for rotation with said spindle 74 as well as for sliding axial movement relative thereto. The sleeve or collet 109 also has mounted thereon a cage 112 in which are mounted spring plungers 113 and 114 engaging at their inner ends with a shiftable abutment 115 (see also Figure 14). The spindle 14 is provided with an elongated slot or passage 116 through which passes a pin 117 carried by a piston rod 118 which extends through a suitable bore formed in the spindle. Secured to the outer end of the piston rod is a piston 119 enclosed within a cylinder 120 secured in any desirable manner to a suitable part of the bearing 81. The cylinder 120 is provided with three ports 121, 122 and 123 (Figure 4) with which are respectively connected the termini of conduits 124, 125 and 126 forming part of the hydraulic control system (Figure 7) and for conveying the hydraulic medium to the cylinder 120 for the operation of the piston therein.

From the foregoing it will be noted that actuation of the piston 119 relative to the cylinder 120 effects the shifting of the collet 109 axially or lengthwise of and relative to the spindle 74 and consequently a shifting of the wheel 107 toward and from the work flange 105. The movement of the collet toward the flange continues until the wheel engages said flange whereupon the plungers 113 and 114 are compressed until the pin 117 engages with and is stopped by the inner end of the slot passage 116.

In order to rigidly tie the two heads after they have been adjusted, and to effect further minute adjustments between the axes of the lapping and control spindles, the face plates 41 and 71 have respectively extending from their lateral edges, ears 127 and 128 (Figure 2) through which are formed tapered bores 129. Extending through said bores are tie rods 130 and 131 having on one end thereof nuts 132 which engage, for example, the plate 71. The other ends of the tie rods 130 and 131 are threaded to receive hand

nuts 133 and 134 (Figures 2 and 3) which abut the plate 41. Actuation of the nuts 133 and 134 in a given direction effects the drawing toward one another of the plates 41 and 71 for springing the said plates and thereby rigidly holding same in positions of adjustment. The tapered bores 129 permit such relative movement between the tie rods 130-131 and the plates 41 and 71, prior to tightening the nuts 133, 134 as is necessitated by the adjustment of the heads about the axes of the guides and also by the oscillatory or tilting adjustment of the carriages; thereby interference from said rods to such adjustment as would be the case should the tie rods substantially fit the said bores 129 is prevented.

As shown in Figure 9, for example, preferably the wheels are peripherally spaced apart or have their opposed operative surfaces make such an angle with each other as to support the work in the trough formed by their peripheries or operative surfaces, during the lapping operation. The work is automatically brought into engagement with the wheels and automatically removed therefrom, for which purpose there is provided a work loading and ejecting mechanism. For supporting the work loading and ejecting mechanism, the bed is provided with a transverse rib 135 (Figure 9) extending crosswise of the bed and underneath the opposed wheels (Figure 8); extending longitudinally of the slot is formed a T-slot 136 receiving the heads of bolts 137 which secure to the bed the bracket 138. This bracket has depending from it and through a suitable aperture in the bed a circular boss 139, better shown in Figure 8, to which is secured one end of a cylinder 140 that encloses a piston 141. The cylinder 140 is closed at its other end by a head 142 through which is formed a port 143 connected to one end of a conduit 144. The boss 139 of bracket 138 is provided with an aperture through which passes a piston rod 145 having its upper end connected with a carrier 146; a suitable seal or stuffing box, as shown in Figure 8, is provided to prevent leakage of the pressure medium throughout the movements of the piston rod. The carrier 146, whose shifting or movement in an up-and-down direction responds to the actuation of piston 141, includes a pair of upstanding cylindrical or sleeve-like arms 147 and 148 encircling posts 149 and 150, respectively, the latter being secured to and extending upwardly from the stationary support or bracket 138.

Accordingly, with the posts 149 and 150 rigidly held in position by the above described construction, they form dependable guiding supports for the carrier 146 and related parts, for as the carrier 146 partakes of movements in an up and down direction (in Figure 8 it is shown in its lowermost position), the long sleeve-like members 147 and 148 slide along the posts 149 and 150, respectively, and insure that the carrier 146 and related parts are dependably and accurately guided during movement thereof and also dependably supported during periods of rest thereof.

Threaded into the posts 149 and 150 are stop screws 151 and 152, respectively, which are thereby adjustable up and down relative to the said posts. The upper ends of the adjusting screws 151 and 152 are engaged by the lower ends of studs or pins 153 and 154, respectively, which are part of a supplemental or safety work rest 155. The rest 155 (Figure 8) is not only a safety rest, but also a part of the loading and ejecting mechanism and, in fact, actually carries the work

during the movement thereof. This rest at the points 156, 157 and 158 (Figure 8) is under-cut so as to pass between the opposed lapping and controlling wheels without in the least engaging said wheels. As was noted above, and during actual grinding, the rest is below the work so that the work is supported by the wheels themselves during the lapping thereof. In addition, the rest 155 has secured to it guide members to prevent inadvertent or premature engagement of the work and lapping wheels and to insure the work contacting first with the regulating or control wheels to be set into rotation thereby and so that it is already rotating when it contacts with the lapping members. These guides consist of a pair of fingers, as is better shown in Figure 9, one being indicated by the reference character 159 and extending vertically from the rest 155 while the other is an inclined finger 160. The fingers 159 and 160 co-operate with one another to form a trough in which the work is disposed during the movement thereof.

To insure proper contact between the work and wheels, there is provided a pressure roller mechanism that engages the work and forces it against the wheels during the lapping operation, but we have so arranged the parts that the roller is disposed in an inoperative or out-of-the-way position to permit replacement of the work on the loading and ejecting mechanism at the conclusion of the lapping operation. For this reason, the tubular posts 147 and 148 each has extending upwardly from it a lug or ear 161 (Figures 9 and 8) to each of which is pivotally secured, each as by the shaft 162, an arm 163. Each arm 163 carries at one end a pin or axle 164 on which is rotatably mounted a roller 165 (Figures 8 and 9). The roller 165 is covered peripherally with a relatively soft non-scratching material, preferably rubber. Each arm 163 has rotatably secured to it a roller 166 (Figure 9) which when the carrier 146 is elevated as indicated in broken lines in Figure 9 engages with an abutment or block 167 carried by the forward end of the regulating wheel carriage 72 for effecting the swinging of the arm 163 in a clockwise direction or from the position shown in full lines in Figure 9 to the position shown in dotted lines therein. This stroke of the oscillation of the arms 163 is against the yielding resistance of springs 168 (Figure 8) having their lower ends 169 connected with tension adjusting bolts 170 carried by the side ends of the carrier 146. The other ends 171 of the springs 168 are connected to chains 172 (Figures 9 and 8) which in turn have their free ends connected to lugs 173 secured to or depending from the under surfaces of the arms 163 respectively, as seen better in Figure 9. The chains 172 between the points of attachment thereof to the arms 163 and to the springs 168 pass over anti-friction rollers 174 carried by the carrier 146 as is better shown in Figure 9.

From the foregoing it will be noted that with the carrier 146 in its work receiving or upward position, the arms 163 are disposed in their inoperative position, thereby not interfering with the placement of the work on the fingers 159 and 160. As the carrier is lowered into operative position the springs 168 swing the arms 163 in counter-clockwise direction as viewed in Figure 9 to bring the pressure rollers 165 into contact with the work, thereby forcing the work into proper operative engagement with the lapping and work rotation controlling wheels.

The bracket or support 138 which supports the

work loading and ejecting mechanism is provided with a cylindrical valve chamber 175 (Figure 10) open at its upper end and containing a by-pass valve 176. This valve has formed therein a passage 177 effective with the valve in one position for connecting the ports 178 and 179 with one another, and effective, with valve in a second position for interrupting the flow between them, see Figure 10. The port 178 intercepts a port 180 which in turn connects with a port 181 to which is secured one end of the hydraulic conduit 124, which has its other end connected with the port 122 (Figures 4 and 7) of the cylinder 120 which controls the axial position of wheel 108 (Figure 4). The port 179 (Figure 10) connects with the port 182 in turn connected with a port 183 which leads into the upper end of the cylinder 140. Connected with the port 183 is one end of an hydraulic conduit 184 which, as will later appear, terminates at a main control and reversing valve. The by-pass valve 176 (shown in section in Figure 8) is provided on opposite ends with counterbores 185 and 186 which are separated by the section 187 of the valve member through which is formed an axially extending hole for receiving a bolt or screw 188. The lower end of the screw 188 is threaded into the supporting bracket 138 (Figure 8) and the shank of the screw has surrounding it and within the counterbore 186 a coil spring 189 of the expansion type, which abuts on one end with the bracket 138 and on its other end with the valve portion 187. The screw 188 has its head disposed within the counterbore 185 and the head is thereby adapted to engage with the valve portion 187 for limiting the movement of the valve upwardly under the influence of the spring 186. The spring 186 tends to dispose the valve in a position for interrupting the flow of the medium through the ports 178 and 179 (Figure 10). In order to shift the valve to the position shown in the drawings (Figures 8 and 10) and against the action of spring 186, the carrier 146 is provided on its under surface with a boss 190 (Figures 8 and 10) in line with the valve 176 and boss 190 engages and shifts the valve downwardly when the carrier 146 is in its operative or downward position, which is shown in Figure 8. When carrier 146 and related parts move upwardly, valve 176 follows such upward movement under the action of spring 186 and to an extent permitted by the head of screw.

The hydraulic circuit is diagrammatically shown in Figure 7 and comprises a pump 191 having connected with its inlet port a conduit 192 which terminates in a sump or tank 193 for the hydraulic medium, preferably oil. The discharge side of the pump 191 is connected by means of a pipe or conduit 194 with a control or reversing valve indicated generally by the numeral 195, and to be later described in detail. The valve 195 is adapted to alternately connect the conduit 194 with the conduits 125 and 184, the former (125) terminating at the port 121 of the cylinder 120 while the latter (184) terminates at the port 183 of the cylinder 140. The remaining conduit 184 or 125 is connected with branch discharge conduits 196 and 197 which are connected with the common return conduit 198 which terminates in the tank or sump 193. From the hydraulic diagram in Figure 7 it will be seen that the conduit 124 connects the port 181 of the by-pass valve with the port 122 of the cylinder 120. It will also be seen that conduit 144 connects the port 143 of the cylinder 140 with the port 123 of the cylinder 120. Also the conduit 184 is connected by the

port 183, shown in Figure 7 diagrammatically as conduit 199, with the cylinder 140.

The cycle of operation of the parts hydraulically actuated is as follows. The by-pass valve 176 is shown in open position, the piston 141 is shown at the lower end of its movement with the work carrier and the work thereon in position in the throat and being operated upon by the wheels, and the piston 119 is shown at its inner position so that the wheel 108 (Figure 4) is operating on the side face of flange 105 of the work piece. As soon as the operation on the work piece being operated upon is completed, the valve 195 (Figure 6) is actuated, by means to be later described, for connecting the pressure medium in the conduit 15 194 with the conduit 125. This then effects an outward movement of the piston 119 (to right in Figure 7 and downwardly in Figure 4) for retracting the wheel 108 and as soon as the wheel is fully retracted, the port 123 (Figures 7 and 4) 20 is uncovered, whereupon the fluid under hydraulic pressure enters the conduit 144 (Figures 7 and 8) to the under side of the piston 141 in the cylinder 140. At the time that piston 119 was retracted, the hydraulic medium ahead of it was expelled from the cylinder 120 into and through the conduit 124, then through ports 178 and 179 of valve mechanism 176 (Figures 7 and 8) and then through conduit 184 to the valve 195, where it became connected with branch and main exhaust 30 conduits 197 and 198, passing to the pump 191 through conduit 192.

The pressure medium in the conduit 144 now effects the upward movement of the piston 141 35 (Figures 7 and 8) carrying with it the carrier 146 with its work piece and elevating the work above the lapping and control wheels so that it may be replaced by an unfinished one. As soon as the carrier is moved upwardly, the spring 186 (Figure 40 8) shifts the by-pass valve 176 upwardly to a position to cut off further flow of the medium from the pipe 124 (Figure 7) through the ports 178 and 179 into the conduit 184 and thereby holding piston 119 (Figures 7 and 4) and consequently the wheel 108 stationary, in a retracted position, and hence out of the position where it had been operating upon the work.

As soon as the work piece is replaced by an unfinished one, the valve 195 is again shifted, this 50 time to the position shown in Figure 7, thereby connecting the main pressure conduit 194 with the conduit 184. The by-pass valve 176 is now in a position to prevent flow through ports 178 and 179 so that the pressure medium in the conduit 55 184 passes through the port or conduit 199 to the upper end of the cylinder 140 (Figures 7 and 8) and effects a descent of the piston 141 and the work loading mechanism controlling it. The work carried by the carrier 146 continues in its 60 movement downwardly toward the wheels until further downward movement is arrested by the wheels (see Figure 9), whereupon the continued downward movement of the carrier 146 depresses the by-pass valve 176 (Figures 8 and 7 and 10) 65 for again permitting or effecting a flow through the ports 178 and 179 (Figure 7) which thereby connects the branch pressure conduit 134 with the conduit 124 for effecting an inward shifting of the piston 119 and the wheel 108 (Figure 4) 70 into operative position. At the conclusion of the grinding operation a repetition of the cycle above described is effected.

The reversing or control valve 195 which is shown diagrammatically in Figure 7 is structural- 75

ly shown in Figure 11. As shown in the latter view, the valve comprises a casing 200 which is bolted to the front of the bed 15 as is clearly shown in the lower left-hand portion of Figure 1, and has pressed into it a bushing 201 (Figure 11) 5 slidable through which is the piston valve 202. The valve 202 is provided with passages 203 and 204 for connecting the port 205 of the bushing with the port 206, with which in turn connects the conduit 184. At this time the port 207 of the bushing is connected by the cannelure 203 with the port 208 which in turn connects through the throttle valve 209 with the exhaust port 210 connected with the conduit 198. Shifting of the 10 valve to its second position from that shown in Figure 11, effects connection of the pressure port 211 by way of the cannelure 203 with the port 207, thereby disconnecting the said port 207 from the exhaust port 210. At this time also the 15 port 206 is connected with the port 212 which is connected through the throttle valve 213 with the port 210 and conduit 198. The pressure ports 205 and 211 are connected by a circumferential groove 214 in the valve bushing and the port 215 with the pressure port 216 formed longitudinally of the casing which in turn is connected 20 with the pump pressure line 194.

The valve 202 (Figures 11 and 15) is axially shifted by means of a lever 217 which is secured 25 to a shaft 218 (Figure 15) rotatably journaled in a bearing 219 formed integrally with the valve casing 200. Secured to the shaft 218 is an arm or lever 220 having formed thereon a tongue 221 adapted to be received in a suitable recess 222 formed in the valve 202. From this it will be seen that actuation of the lever 217 about the axis of the shaft 218 correspondingly shifts the lever or arm 222 for thereby axially shifting the valve 202 through its bushing. In order to hold the valve in its various operative positions, 30 it is provided with a pair of circumferential detent grooves 223 and 224 (Figure 11) adapted to co-operate with a spring pressed plunger 225 carried by the casing 200, plunger 225 entering one or the other groove according to the stroke given the valve.

As was suggested above, an abrasive wheel is composed of grains of various grit and grade which are bonded together by a suitable bonding material into a homogeneous mass. This wheel is then rotated at a given rate of speed while in operative engagement with a work piece which is also rotated at a given rate of speed, which bears a definite relation to the speed of rotation of the wheel. In performing grinding operations the wheel is rotated at a surface speed of 6000 feet or more a minute while the work is rotated at but 150 peripheral feet a minute. This produces a grinding finish on the work consisting of alternate grooves and ridges, the disadvantage 35 of which finish is fully set forth above. By materially varying the ratio between the speeds of rotation of the work and wheel, the finish on the work is materially improved. It has been found in practice that the nearer these two surface speeds approach the ratio of one to one, the finer and flatter becomes the finish on the work. In other words, there is but a slight differential in peripheral speed between the lapping wheels and the work, which ratio is determined by the size 40 of the work and is such that the speed of the parts does not tend to drag the work down between the wheels. The speed of rotation of the work is effected and controlled by the regulating or friction control wheels 36 wherefor the sur-

face speed of these wheels must be below the surface speed of the operating or lapping wheels in order to establish the proper surface speed relation between the work and the said lapping wheels.

In ordinary grinding practice the work contacts with the peripheral surface of a grinding wheel along a line parallel with the axis of the grinding wheel which axis and that of the work are parallel whereby any vibration in these parts 10 results in ridges and valleys extending the full length thereof. These high portions of the work surface are commercially known as chatter and cause the work, when put to use, to wear rapidly since the contact therewith is not a true 15 surface contact but on the tops of the ridges, which will wear until they are reduced to the level of the valleys therebetween. With the present machine, the axis of the peripherally operative lapping wheel is disposed at a relatively 20 large angle to the axis of the work, thereby causing the lapping wheels to contact the work along a diagonal line. In other words, the lapping wheels simultaneously engage the tops of a plurality of ridges or chatters and simultaneously reduce 25 said ridges to the depth of the valleys. The relative arrangement of the parts from which the above-mentioned diagonal or oblique lapping action takes place is better shown in Figure 6, in which the tilt of the axis of the operating or lapping members 52, 51 and 50 relative to the axis of the parts of the work piece engaged thereby is better shown. Throughout the length of each peripherally operating lapping member and along its line of contact with the cylindrical 30 portion or portions of the work piece, the lapping member, due to the above mentioned relative tilt between its axis and the axis of the work piece, performs this lapping action in that a point on the operating surface on the lapping member 40 moves obliquely to the circumferential ridges and valleys (which result from the grinding of the work prior to being subjected to the operation of our apparatus) but while the work piece is being rotated by the control member or members (members 86, 84 and 83, in Figure 6, respectively, juxtaposed to the lapping members 52, 51 and 50) and thereby the reduction or leveling off of the ridges is dependably and quickly achieved. The action of the abrasive particles 45 throughout the extent of the line of contact between the work and the lapping member is thus made to be effective in a direction oblique to this line of contact and preferably not parallel to the direction in which the grooves or valleys and their intervening ridges extend circumferentially about the work piece. The effect is somewhat like wiping this obliqueness of action, as the work piece continues to rotate, continuously around the whole cylindrical portion of the 50 work piece being operated upon, and the abrasive particles are thus dependably caused to traverse (rather than to line up with) the ridges and valleys. From this it will be seen that the work produced by this machine is not only 55 devoid of the circumferential marks, but of the longitudinal chatter marks as well.

To effect the proper differential between the spindles 44 and 74 of the lapping and control wheels, they are provided with a suitable drive 60 wheel which includes the provision on their rear ends with sprockets 226 and 227 (Figure 4). Trained about the sprocket 226 is a sprocket chain 228 in turn trained about a sprocket 229 on the end of a driven shaft 230 (Figure 12). The 65

shaft 230 is rotatably journaled in bearings provided by a speed changing box or casing 231 (Figure 12) secured to the rear wall of the bed 15. The sprocket 229 has formed integrally therewith or secured thereto an enlarged flange 232 constituting one member of a safety drive clutch co-operating with a clutch member 233 secured to a pulley or sheave 234. The sheave 234 is of the multiple belt type and has trained thereabout the flexible drive members or belts 235 which are also trained about a driving sprocket on the end of the motor shaft extending from driving motor 236 secured to the right hand end of the machine bed, as seen in Figures 1, 2 and 3. From the foregoing it will be noted that the spindle 44 and consequently the operating or lapping wheels secured thereto are directly driven from the prime mover or motor 236 through the belts 235, pulley 234, safety clutch 232-233, and the sprocket and chain mechanism from the shaft 230.

The shaft 230 (Figure 12) extends into and through the variable speed box 231 and is provided with a driving mechanism for effecting the speed changes or reductions. As seen in Figure 12, this driving mechanism comprises a pair of cone drive discs 237 and 238 having formed on their opposed conical faces radial grooves 239 with which engage the dogs 240 of the flexible power transmission chain 241. The dogs 240 of the chain 241 in turn engage with similar radial grooves 242 formed on the opposed faces of driven cone members 243 and 244 which are similar in all respects to the cone members 237 and 238. These other cone members 243-244 are keyed or otherwise secured to a shaft 245 rotatably journaled in the walls of the speed change box 231. The driven shaft 245 has on a projecting end thereof a sprocket 246 about which is trained a sprocket chain 247 in turn passing upwardly about the sprocket 227 on the friction control wheel spindle 74 (Figure 4). The speed of the shaft 245, as compared to the speed of the shaft 230, depends upon the separation of the opposed members 237-238 and 243-244 or in other words, if the driving dogs engage the opposed cone members at a central point as respects the length of the radial grooves 239 and 242, the speed ratio of shafts 230 and 245 and hence of the lapping and control wheels will be the ratio of one to one, while if the members 237 and 238 were separated to permit the driving dogs to engage the radial grooves near their inner termini and the members 243 and 244 were actuated toward one another to cause said dogs to engage in the radial grooves near their outer termini, then the speed of the shaft 245 is less than the speed of the shaft 230. Conversely if these driving and driven cone members are oppositely set or actuated, a change in ratio in opposite direction between these shafts results.

From the foregoing it will be seen that the operating or lapping wheels are rotated at a constant speed while the regulating members may be rotated at variable speeds to thereby establish the desired ratio of speed between the work and the lapping members. This variation in speed is effected by, as suggested above, varying the separation of the driving and driven cone members. This separation is accomplished by two pairs of arms 248 and 249 (Figure 12), the former pair being connected to one another by the pins 250 while the latter are correspondingly connected by pins 251. The said arms are pivoted at a point centrally between the axes of the shafts 230 and

245 as at 252 and 253. The arms 248 are pivotally connected at their outer end at 254 to the driving member 237 and are pivoted near their other ends at 255 to the driven member 243 and have a sliding connection at 256 with a nut 257 in threaded engagement with the screw 258. The arms 249 are pivoted at 259 to the driving member 238 and at 260 with the driven member 244. The arms 249 also have a sliding connection 261 with a nut 262 on the screw 263. The screws 258 and 263 are of opposite hand and are formed integral with or connected to a shaft 264 so that rotation of the shaft and consequently of the screws in a given direction actuates or moves their respective nuts 257 and 262 in opposite directions, for example, toward each other, thereby simultaneously shifting the members 237 and 238 away from one another and shifting the members 243 and 244 toward one another, or vice versa. The shaft 264 is rotatably journaled in suitable bearings provided by the walls of the casing 231, and extends beyond the walls where it receives at one end the manually operable knob 265 (Figure 12) and at the other end a sprocket 266. The knob 265 may be resorted to in emergency since it is down in back of the bed, while the sprocket 266 is generally employed for more conveniently effecting the necessary or desired adjustment of the parts.

For this latter purpose the sprocket 266 has 30 extending about it a chain 267 which is also trained about a sprocket 268 (see now Figure 5) secured to a shaft 269. The shaft 269 is rotated in suitable bearings provided by the walls of the bed 15, and beyond the front wall of the bed, or 35 the front bearings 270, the shaft is extended to receive a manually actuatable lever 271 (see also Figure 1). The lever 271 is provided with a pointer 272 co-operating with a dial 273 for readily determining the relative adjustment of the 40 parts.

From the foregoing it will be seen that the speed of the wheels may be readily changed from the operator's position or station in front of the machine bed where he is at all times stationed 45 during the operation of the machine.

In order to properly tension the belts 235 and in order to take up any stretch in the belts, the prime mover or motor 236 (Figures 1 and 3) is in effect mounted on a swivel bracket or up-ended 50 platform 214 pivoted at 215 to the bed 15. The upper end of the platform is provided with a fork carrying a nut 216 in threaded engagement with a screw 217 projecting outwardly from the bed 15. Adjustment of the platform 214 to the 55 left about the axis 215 effects the proper tightening or tensioning of the belts 235.

The pulley 234 has extending from it a transmission belt 278 (Figure 12) trained about a suitable pulley associated with the pump 279 60 (Figure 1) pivotally mounted at 280 to the right hand end of the bed, as seen in Figure 1. This pump 279 is also tiltable toward or away from the pulley 234 for properly tightening or tensioning the belt 278, for which purpose it has extending from it an arm 281 (Figure 1) through which extends an adjustable tightening screw 282 co-operating with a bracket 283 or other fixed part of the machine for effecting the desired adjustment of the pump 279. 70

From the foregoing the construction and operation of our apparatus will be clear and it will be seen that there has been provided in this invention a lapping machine in which the various objects above set forth or indicated, together 75

with many thoroughly practical advantages, are successfully achieved. It will be seen that the apparatus is of a thoroughly practical nature, is capable of dependably operating upon work pieces of peculiar or irregular shapes or conformations, and, moreover, that the apparatus is capable of such flexibility of adjustment or of interrelation of the various parts thereof that it is well adapted to meet the widely varying types and characters of work pieces, particularly cylindrical work pieces that have shoulders or collared parts thereon, all without detracting from accuracy or quality of result.

What is claimed is:

15. 1. In a lapping machine of the class described, the combination of a pair of opposed spindles, a plurality of lapping wheels on one spindle, a plurality of control wheels on the other spindle, said spindles being spaced from one another to space the peripheries of said lapping and control wheels a distance less than the diameter of the work being operated upon whereby the work is supported on the peripheries of said wheels, means for rotating said wheels at speeds insufficient to draw the work down between them, loading and ejecting means for placing the work in position on the wheels and removing same from said wheels, and hydraulically actuated means for operating said work loading and ejecting means.
20. 2. In a lapping machine for lapping the portion of a cylindrical work piece adjacent a shoulder thereon, the combination of a cylindrical lapping member rotatable about an axis to dispose said member in a vertical plane and engaging said work piece on one side of said portion with said shoulder extending to one side of said lapping member, an opposed friction control member for engaging said portion of the work on the other side thereof to effect and control its rotation during the lapping operation, means for effecting the rotation of said members at slightly differential surface speeds, and means for lapping a face of said shoulder as said work piece is rotated by said control member and hence as said shoulder is also rotated.
25. 3. In a lapping machine of the class described, the combination with a bed, of a pair of heads mounted thereon, means for effecting adjustment of one of said heads in a direction toward or away from the other, a spindle rotatably mounted in each head, a lapping member on one of the spindles for lapping the cylindrical portion of a work piece that is disposed adjacent a shoulder, and a friction control and lapping member on the other spindle for engagement respectively with the cylindrical portion of the work and with shoulder for simultaneously effecting and controlling the rotation of the work and for lapping the shoulder portion adjacent thereto.
30. 4. In a lapping machine of the class described, the combination with a bed, of a pair of heads mounted thereon, means for effecting adjustment of one of said heads in a direction toward or away from the other, a spindle rotatably mounted in each head, a lapping member on one of the spindles for lapping the cylindrical portion of a work piece that is disposed adjacent a collar, a friction control and lapping member on the other spindle for engagement respectively with the cylindrical portion of the work and with the adjacent face of the collar for simultaneously effecting and controlling the rotation of the work and for lapping the said adjacent face of the collar, and a second lapping wheel spaced from

said second-mentioned lapping member in the direction of the axis of the latter and thereby positioned for engaging the opposite face of said collar for effecting the lapping thereof.

5. In a lapping machine of the class described, the combination with a bed, of a pair of heads mounted thereon, means for effecting adjustment of one of said heads in a direction toward or away from the other, a spindle rotatably mounted in each head, a lapping member on one of the spindles for lapping the cylindrical portion of a work piece that is disposed adjacent a collar, a friction control and lapping member on the other spindle for engagement respectively with the cylindrical portion of the work and with the adjacent face of the collar for simultaneously effecting and controlling the rotation of the work and for lapping, the said adjacent face of the collar, a second lapping wheel spaced from said second-mentioned lapping member in the direction of the axis of the latter and thereby positioned for engaging the opposite face of said collar for effecting the lapping thereof, and means for shifting the second lapping member toward and from the collar to permit a replace- 25 ment of the work.

6. In a lapping machine of the class described, the combination with a bed, of a pair of heads mounted thereon for independent movement relative thereto toward and from one another, additional independent means for pivotally securing the heads to the bed whereby the said heads may be independently swung relative to the bed, a carriage pivotally mounted on each head for swinging adjustment relative thereto, a spindle rotatably journaled in each head, a lapping member carried by one of the spindles, a friction control member carried by the other spindle, and means for adjusting the positions of the heads to dispose the peripheries of the lapping 40 and control wheels from one another a distance less than the diameter of the work whereby it may be supported on the peripheries of the wheels.

7. In a lapping machine of the class described, the combination with a bed, of a pair of heads mounted thereon for independent movement relative thereto toward and from one another, additional independent means for pivotally securing the heads to the bed whereby the said 50 heads may be independently swung relative to the bed, a carriage pivotally mounted on each head for swinging adjustment relative thereto, a spindle rotatably journaled in each head, a lapping member carried by one of the spindles, a friction control member carried by the other spindle, means for adjusting the positions of the heads to dispose the peripheries of the lapping and control wheels from one another a distance less than the diameter of the work whereby it 60 may be supported on the peripheries of the wheels, and yielding means for yieldingly holding the work in contact with the peripheries of said wheels.

8. In a lapping machine of the class described, the combination with a bed, of a pair of heads mounted thereon for independent movement relative thereto toward and from the one another, additional independent means for pivotally securing the heads to the bed whereby the 70 said heads may be independently swung relative to the bed, a carriage pivotally mounted on each head for swinging adjustment relative thereto, a spindle rotatably journaled in each head, a lapping member carried by one of the spindles, a 75

friction control member carried by the other spindle, means for adjusting the positions of the heads to dispose the peripheries of the lapping and control wheels from one another a distance less than the diameter of the work whereby it may be supported on the peripheries of the wheels, yielding means for yieldingly holding the work in contact with the peripheries of said wheels, and a loading and ejecting mechanism operable for loading the work on the wheels and ejecting same therefrom at the conclusion of the lapping operation.

9. In a lapping machine for simultaneously lapping a plurality of spaced portions on a work piece one of which portions is adjacent a flange and for simultaneously lapping the sides of said flange, comprising a lapping member for each spaced portion of the work piece, an opposed control member for each spaced portion of the shaft, the control member for the portion of the shaft adjacent the flange being utilized for lapping the adjacent face of the flange, and means for rotating the lapping and control members at speeds having a relatively low differential between them.

10. In a lapping machine for simultaneously lapping a plurality of spaced portions on a work piece one of which portions is adjacent a flange and for simultaneously lapping the sides of said flange, comprising a lapping member for each spaced portion of the work piece, an opposed control member for each spaced portion of the shaft, the control member for the portion of the shaft adjacent the flange being utilized for lapping the adjacent face of the flange, means for rotating the lapping and control members at speeds having a relatively low differential between them, and an additional lapping member for lapping the remaining face of the flange.

11. In a lapping machine for simultaneously lapping a plurality of spaced portions on a work piece one of which portions is adjacent a flange and for simultaneously lapping the sides of said flange, comprising a lapping member for each spaced portion of the work piece, an opposed control member for each spaced portion of the shaft, the control member for the portion of the shaft adjacent the flange being utilized for lapping the adjacent face of the flange, means for rotating the lapping and control members at speeds having a relatively low differential between them, an additional lapping member for lapping the remaining face of the flange, and means for actuating the additional lapping member toward and from the flange.

12. In a lapping machine for simultaneously lapping a plurality of spaced portions on a work piece one of which portions is adjacent a flange and for simultaneously lapping the sides of said flange, comprising a lapping member for each spaced portion of the work piece, an opposed control member for each spaced portion of the shaft, the control member for the portion of the shaft adjacent the flange being utilized for lapping the adjacent face of the flange, means for rotating the lapping and control members at speeds having a relatively low differential between them, an additional lapping member for lapping the remaining face of the flange, means for actuating the additional lapping member toward and from the flange, a loading and ejecting mechanism for sequentially positioning the work piece in operative position as respects the lapping and control members and for removing same from the operative position, and means

interconnecting the operation of the additional lapping member and the loading and ejecting mechanism to retract the lapping member prior to the ejection of the work piece and advance same after the positioning thereof.

13. In a lapping machine for simultaneously lapping a plurality of spaced portions on a work piece one of which portions is adjacent a flange and for simultaneously lapping the sides of said flange, comprising a lapping member for each spaced portion of the work piece, an opposed control member for each spaced portion of the work piece, the control member for the portion of the work piece adjacent the flange being utilized for lapping the adjacent face of the flange, means for rotating the lapping and control members at speeds having a relatively low differential between them, an additional lapping member for lapping the remaining face of the flange, means for actuating the additional lapping member toward and from the flange, a loading and ejecting mechanism for sequentially positioning the work piece in operative position as respects the lapping and control members and for removing same from the operative position, means interconnecting the operation of the additional lapping member and the loading and ejecting mechanism to retract the lapping member prior to the ejection of the work piece and advance same after the positioning thereof, and hydraulically controlled means for effecting the operation of the loading and ejecting mechanism and the shifting of the additional lapping member.

14. In a lapping machine of the class described, the combination with opposed lapping and control members spaced from one another a distance to support a work piece on the peripheries thereof, of an hydraulic loading and ejecting mechanism comprising a carrier, a piston operatively connected with the carrier whereby movement in opposite directions effects a corresponding movement of the carrier, a carrier blade associated with the carrier, means on the carrier blade to prevent inadvertent contact between the work and the wheels, and pressure means for engaging the work when in position between said opposed lapping and control members for yieldingly holding the work in contact therewith.

15. In a lapping machine of the class described, the combination of a bed, bearing surfaces on said bed at opposite ends thereof, a lapping head disposed on one of said bearing surfaces, a control head disposed on the other of said surfaces, the lapping head being formed on its under surface with a guideway, a guide received in said way and having one end pivoted to the bearing surface, means carried by the bed for effecting adjustment of the guide about its pivot, and co-operating means carried by the guide and head for effecting the adjustment of the head relative to the bearing surface and guide along an axis determined by the angular adjustment of the guide.

16. In a lapping machine of the class described, the combination of a bed, bearing surfaces on said bed at opposite ends thereof, a lapping head disposed on one of said bearing surfaces, a control head disposed on the other of said surfaces, the lapping head being formed on its under surface with a guideway, a guide received in said way and having one end pivoted to the bearing surface, means carried by the bed for effecting adjustment of the guide about its pivot, co-operating means carried by the guide and head for effecting the adjustment of the head relative to

the bearing surface and guide along an axis determined by the angular adjustment of the guide, and means associated with said head for securing same in position on the bearing surface after adjustment.

17. In a lapping machine of the class described, the combination of a bed, bearing surfaces or said bed at opposite ends thereof, a lapping head disposed on one of said bearing surfaces, a control head disposed on the other of said surfaces, the lapping head being formed on its under surface with a guideway, a guide received in said way and having one end pivoted to the bearing surface, means carried by the bed for effecting adjustment of the guide about its pivot, co-operating means carried by the guide and head for effecting the adjustment of the head relative to the bearing surface and guide along an axis determined by the angular adjustment of the guide, means associated with said head for securing same in position on the bearing surface after adjustment, a spindle carriage pivotally secured to said head, and means for adjusting the carriage about its pivotal support.

18. In a lapping machine of the class described, the combination with a bed having a bearing surface thereon, of a head mounted on said bearing surface for sliding movement relative thereto, said head having a guideway formed on its under surface, a guide pivoted to the bearing and received in the head guideway, means pivotally securing the guide to the head whereby it may be adjusted for disposing the axis of movement of the head at angles, a carriage pivotally carried by

30 the head, a spindle rotatably journaled in the carriage, and means for adjusting the carriage relative to the head in a direction axially of the spindle.

19. In a lapping machine of the class described, 40 the combination of a bed, a pair of heads mounted on said bed, a spindle rotatably journaled in each head, a lapping member on one spindle, a work rotation controlling member on the other spindle, means for adjusting the position of one of said heads in a direction toward or away from the other, and means for adjusting one of said heads in a substantially horizontal plane whereby the axis of one of the spindles may be disposed angularly to the other in said horizontal plane 50 and whereby the said axes of the spindles may be disposed parallel to one another.

20. In a lapping machine of the class described, the combination of a bed, a pair of heads mounted on said bed, a spindle rotatably journaled in each head, a lapping member on one spindle, a work rotation controlling member on the other spindle, means for adjusting the position of one of said heads in a direction toward or away from the other, means for adjusting one of said heads 60 in a substantially horizontal plane whereby the axis of one of the spindles may be disposed angularly to the other in said horizontal plane and whereby the said axes of the spindles may be disposed parallel to one another, and means for adjusting one of the heads in a direction to achieve a skewing of the axes of the spindles relative to one another.

21. In a lapping machine of the class described, 70 the combination of a bed, a pair of heads mounted on the bed, a spindle rotatably journaled in each head respectively provided with a lapping member and a work rotation frictional control member, means for adjusting one of said heads toward and away from the other to permit the 75 disposition of the peripheries of the lapping and

control members in close proximity to support a work piece thereon, means for rotating one of said spindles at a given speed, means for rotating the other spindle at variable speeds and means connecting the driving means of said two spindles whereby the variation of the second spindle is upwardly and downwardly with respect to the speed of the first spindle.

22. In a lapping machine of the class described 10 for simultaneously lapping a cylindrical and collared portion of a work piece, the combination of a bed, a pair of opposed lapping and work rotation control members mounted on the bed, said members respectively lapping the cylindrical portion of work and controlling the rotation thereof 15 during the said lapping operation, a second lapping member for lapping the face of the collar portion of the work simultaneously with the lapping of the cylindrical portion thereof, means for loading and ejecting the work in operative relation with the lapping and control members, and means for shifting the second lapping member into and out of operative relation with the face 20 of the collar.

23. In a lapping machine of the class described 25 for simultaneously lapping a cylindrical and collared portion of a work piece, the combination of a bed, a pair of opposed lapping and work rotation control members mounted on the bed, said members respectively lapping the cylindrical portion of work and controlling the rotation thereof 30 during the said lapping operation, a second lapping member for lapping the face of the collar portion of the work simultaneously with the lapping of the cylindrical portion thereof, means for loading and ejecting the work in operative relation with the lapping and control members, means for shifting the second lapping member into and out of operative relation with the face 35 of the collar, and means for interlocking the loading and ejecting mechanism with the means for shifting the second lapping member whereby they are sequentially operated.

24. In a lapping machine of the class described 45 for simultaneously lapping a cylindrical and collared portion of a work piece, the combination of a bed, a pair of opposed lapping and work rotation control members mounted on the bed, said members respectively lapping the cylindrical portion of work and controlling the rotation thereof 50 during the said lapping operation, a second lapping member for lapping the face of the collar portion of the work simultaneously with the lapping of the cylindrical portion thereof, means for loading and ejecting the work in 55 operative relation with the lapping and control members, means for shifting the second lapping member into and out of operative relation with the face of the collar, and means for interlocking the loading and ejecting mechanism with the means 60 for shifting the second lapping member whereby they are sequentially operated, said first-mentioned means comprising hydraulically actuated mechanisms associated with said loading and ejecting mechanism and the second lapping member.

25. In a lapping machine of the class described for simultaneously lapping a cylindrical and collared portion of a work piece, the combination of a bed, a pair of opposed lapping and 70 work rotation control members mounted on the bed, said members respectively lapping the cylindrical portion of work and controlling the rotation thereof during the said lapping operation, a second lapping member for lapping the face 75

of the collar portion of the work simultaneously with the lapping of the cylindrical portion thereof, means for loading and ejecting the work in operative relation with the lapping and control members, means for shifting the second lapping member into and out of operative relation with the face of the collar, means for interlocking the loading and ejecting mechanism with the means for shifting the second lapping member whereby they are sequentially operated, said first-mentioned means comprising hydraulically actuated mechanisms associated with said loading and ejecting mechanism and the second lapping member, an hydraulical pressure system for actuating the said hydraulically actuated mechanism, and a valve in said pressure system for initiating the reverse operations thereof.

26. In a lapping machine, the combination with opposed lapping and control members spaced from one another by a distance to support a work piece on the adjacent peripheries thereof, of work loading and ejecting mechanism comprising a work carrier, means mounting the work carrier for movement in up and down direction respectively to move a work piece upwardly out of engagement with said members or downwardly into engagement therewith, means for effecting said up and down movement of said work carrier, means for engaging the work when in position between said opposed lapping and control members for yieldably pressing the work into contact with the peripheries thereof, and means operative upon movement of said carrier in upward direction for removing said work-pressing means out of engagement with the work.

27. In a lapping machine, the combination with opposed lapping and control members spaced from one another by a distance to form, by the peripheries of said members, a trough-like work-receiving throat whose narrower portion is of a dimension less than the diameter of the work to be lapped, means for moving work in a direction from the larger portion toward the narrower portion of said work-receiving throat, thereby to present the work to the opposed peripheries of said members, and thereafter moving it in reverse direction to remove the work from said throat, means for effecting rotation of said members at slightly differential surface speeds and with the adjacent peripheries moving in opposite directions, and means for pressing the work when positioned in said work-receiving throat and when in engagement with the peripheries of said members in a direction toward the narrower portion of said throat.

28. A lapping machine as claimed in claim 27 in which there is provided means mounting said work-pressing means to cause it to partake of movement with said work-moving means, and means operating, when said work-moving means moves the work in a direction toward the larger portion of the work-receiving throat, to move said work-pressing means out of engagement with the work and thereby permit removal thereof from said work-moving means.

29. A lapping machine as claimed in claim 27 in which there is provided spring means for yieldably operating upon said work-pressing means to cause the latter yieldingly to press the work toward the narrower portion of said work-receiving throat, and means operating, when said work-moving means moves the work in a direction toward the larger portion of the work-receiving throat, to overcome the action of said

spring means and to move said work-pressing means out of engagement with the work.

30. A lapping machine as claimed in claim 27 in which the work-pressing means comprises a pivotally mounted arm having rotatably mounted thereon a roller for directly engaging the work, and means forcing said arm to swing in a direction to cause said roller, when the work-moving means has moved the work into said work-receiving throat, to exert pressure on the work in a direction toward the narrower portion of the throat.

31. A lapping machine as claimed in claim 27 in which the work-pressing means comprises a pivotally mounted arm having rotatably mounted thereon a roller for directly engaging the work, means forcing said arm to swing in a direction to cause said roller, when the work-moving means has moved the work into said work-receiving throat, to exert pressure on the work in a direction toward the narrower portion of the throat, and means operating, when said work-moving means moves the work in a direction toward the larger portion of said work-receiving throat, to swing said arm in reverse direction and thereby remove said roller from engagement with the work.

32. In a lapping machine for simultaneously lapping a cylindrical portion and a flange portion of a work piece, in combination, opposed lapping and control members between the adjacent operative surfaces of which the cylindrical portion of the work piece is engaged, means for rotating said members so as to give said adjacent operative surfaces surface speeds having a relatively low differential therebetween and to cause them to move in opposite directions relative to the work piece engaged therebetween, whereby the lapping member laps said cylindrical portion of the work piece while said control member effects and controls the rotation of the work piece and hence of the flange portion thereof, a pair of spaced lapping members between which said rotating flange portion extends, and means for driving said pair of lapping members to cause them to effect a lapping operation on the two side faces of said flange portion during the rotation thereof by said control member.

33. In a lapping machine for simultaneously lapping a cylindrical portion and a flange portion of a work piece, in combination, opposed lapping and control members between the adjacent operative surfaces of which the cylindrical portion of the work piece is engaged, at least one of said members having a shaft and means for rotatably supporting said shaft, means for rotating said members so as to give said adjacent operative surfaces surface speeds having a relatively low differential therebetween and to cause them to move in opposite directions relative to the work piece engaged thereby, whereby the lapping member laps said cylindrical portion of the work piece while said control member effects and controls the rotation of the work piece and hence of the flange portion thereof, a lapping member for operating upon a side face of said flange portion as the work piece with the latter is rotated by said control member, means comprising a sleeve-like member for supporting said last-mentioned lapping member, said sleeve-like member being slidably received upon said shaft, means forming a driving connection between said sleeve-like member and said shaft whereby said last-mentioned lapping member may be driven, and means for controlling the position of said sleeve-like mem- 75

ber lengthwise of said shaft to bring said last-mentioned lapping member into or out of operative relation to the side face of said flange portion of the work piece.

34. In a lapping machine for simultaneously lapping a cylindrical portion and a flange portion of a work piece, in combination, opposed lapping and control members between the adjacent operative surfaces of which the cylindrical portion of the work piece is engaged, means including shafts for rotatably supporting said members, means for rotating said members so as to give said adjacent operative surfaces surface speeds having a relatively low differential therebetween and to cause them to move in opposite directions relative to the work piece engaged thereby, whereby the lapping member laps said cylindrical portion of the work piece while said control member effects and controls the rotation of the work piece and hence of the flange portion thereof, a driven lapping member having an operative surface spaced in the direction of the axis of the work piece from said opposed lapping and control members and adapted to operate upon a side face of said flange portion, means movably mounting said last-mentioned lapping member for movement into or out of operative relation to the side face of said flange portion, means for moving a work piece to bring the said cylindrical portion thereof into engagement with the adjacent operative surfaces of said opposed lapping and control members and thereby effecting a lapping and rotation-control of said cylindrical portion and thereby setting said flange portion into rotation, and means for moving said second-mentioned lapping member to bring its operative surface into lapping engagement with the side face of said rotating flange portion.
35. In a lapping machine for simultaneously lapping a cylindrical portion and a flange portion of a work piece, in combination, opposed lapping and control members between the adjacent operative surfaces of which the cylindrical

portion of the work piece is engaged, means for rotating said members so as to give said adjacent operative surfaces surface speeds having a relatively low differential therebetween and to cause them to move in opposite directions relative to the work piece engaged thereby, whereby the lapping member laps said cylindrical portion of the work piece while said control member effects and controls the rotation of the work piece and hence of the flange portion thereof, a driven lapping member having an operative surface spaced in the direction of the axis of the work piece from said opposed lapping and control members and adapted to operate upon a side face of said flange portion, means movably mounting said last-mentioned lapping member for movement into or out of operative relation to the side face of said flange portion, means for moving a work piece to bring the said cylindrical portion thereof into engagement with the adjacent operative surfaces of said opposed lapping and control members and thereby effecting a lapping and rotation-control of said cylindrical portion and thereby setting said flange portion into rotation, and means for moving said second-mentioned lapping member to bring its operative surface into lapping engagement with the side face of said rotating flange portion.

36. A lapping machine as claimed in claim 35 in which there are provided means interconnecting the operation of said work-moving means and of said moving means for said second-mentioned lapping member to effect actuation thereof sequentially in the order named.
